UNITED STATES PATENT OFFICE.

MARTHA COLSTROM, OF OSAGE CITY, KANSAS.

OVERALLS.

SPECIFICATION forming part of Letters Patent No. 784,615, dated March 14, 1905.

Application filed June 17, 1904. Serial No. 213,013.

To all whom it may concern:

Be it known that I, MARTHA COLSTROM, a citizen of the United States, residing at Osage City, in the county of Osage and State of Kansas, have invented new and useful Overalls, of which the following is a specification.

This invention relates generally to overalls, and particularly to that class presenting in a single structure a jacket or waist and a pair of trousers.

The aim of this invention is to present a novel form of combined overalls and jacket or waist, adapted more particularly for use by boys, the objects had in view being to facilitate dressing and undressing, to dispense, if desired, with the employment of buttons, to obviate waste in cutting, thus to cheapen the cost of production of the garment, and finally to produce a neat, durable, cheap, and inexpensive garment embodying all of the desirable features named.

With the above and other objects in view, as will appear as the nature of the invention is better understood, the same consists in the novel construction and combination of parts of a pair of overalls and jacket, as will be hereinafter fully described and claimed.

In the accompanying drawings, forming a part of this specification, and in which like characters of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in front elevation of the garment. Fig. 2 is a rear elevation with the flap portion of the trousers dropped and the edges of the sides of the jacket turned back to display the fastening means.

Referring to the drawings, 1 designates generally the jacket or waist of the garment, and 2 the trousers. The jacket is provided with arms 3 and with a collar 4 and along the inner surface of one side of the jacket are se-

cured fastening devices, in this instance hooks 6 to engage with eyes 7 on the inner surface 50 of the other side of the jacket. In order to brace the front of the jacket against ripping, there is combined with it a stay 8, which extends from or near the collar to a point adjacent to the waistband 9 of the trousers, at 55 which point a transverse reinforce 10 is disposed, beneath which the lower end of the stay is secured. The jacket and trousers are made from one piece of material and the back of the trousers is provided with a drop-flap 60 11, which when properly positioned upon the person of the wearer extends some distance upward and beyond the lower edges 12 of the jacket sides, thereby to prevent the latter parts from working upward and without the 65 trousers. Combined with the upper edge of the flap is a belt 13; the terminals of which extend outward from the flap in opposite directions and are designed to engage keepers or loops 14, secured to the sides of the trousers, the free ends of the belt being held together by any suitable fastening device, such as a button, buckle, or a hook and eye, and as this will be readily understood detailed illustration of any particular form of fastening device is deemed unnecessary.

By the arrangement shown an exceedingly strong, cheap, and practical garment is presented and one which may readily be manufactured and be repaired in case of injury.

Having thus described the invention, what is claimed is—

A one-piece garment embodying a jacket opened down its back and having fastening devices inset from the edges thus to form an overlapping flap which operates both to shield the fastening devices from view and also to increase the thickness of the garment at that point, the front of the jacket and trousers being continuous, the same being made of a 85 single piece of material and the jacket being vertically reinforced at its front by a stay extending from the neck to a point near the crotch and transversely reinforced by a stay located at the lower terminal of the first-named stay and secured thereto, the rear por-

tion of the trousers being provided with a drop-flap to inclose the lower end of the jacket, keepers or loops secured to the sides of the jacket, and a fastening-band secured to 5 the upper edge of the flap and passing through the keepers or loops at the front of the garment.

In testimony that I claim the foregoing as my own I have hereto affixed my signature in the presence of two witnesses.

MARTHA COLSTROM.
